UNITED STATES PATENT OFFICE.

EINO SALMINEN, OF BUFFALO, NEW YORK, ASSIGNOR TO AUGUST BECKER, OF BUFFALO,
NEW YORK.

DESIGN FOR AN AEROPLANE-BODY.

53,137.

Specification for Design.

Patented Mar. 25, 1919.

Application filed June 10, 1918. Serial No. 239,331. Term of patent 14 years.

To all whom it may concern:

Be it known that I, EINO SALMINEN, a citizen of Finland, residing at Buffalo, in the county of Erie and State of New York, have invented a new, original, and ornamental Design for Aeroplane-Bodies, of which the following is a specification.

This invention relates to a new, original and ornamental design for the body (including the lateral wing portions) of an aeroplane.

Figures 1, 2 and 3 of the drawings are respectively a plan view, side elevation and front elevation of an aeroplane body, showing my design.

I claim—

The ornamental design for an aeroplane body, substantially as shown.

EINO SALMINEN.
